UNITED STATES PATENT OFFICE.

MAX SINGELMANN, OF CHICAGO, ILLINOIS.

AIRSHIP.

1,217,518.

Specification of Letters Patent. Patented Feb. 27, 1917.

Application filed January 2, 1914. Serial No. 810,087.

To all whom it may concern:

Be it known that I, MAX SINGELMANN, a subject of Emperor William II of Germany, residing at Chicago, in the county of Cook 5 and State of Illinois, have invented a new and useful Airship, of which the following is a specification.

My invention relates to air ships in which only mechanical power is employed in connection with suitable planes or wings to support and propel the same above the ground and the objects of my improvements are first, to make the planes or wings movable with relation to the body of the device; second, to so shape the movable planes or wings that their movement will lift and propel the device along; third, to make an air ship which cannot fall with dangerous speed; fourth, to make a simple, efficient and durable device and other features to become apparent from the description to follow.

Unlike the common aeroplane my air ship does not depend wholly upon its speed through the air for its buoyancy but the 25 planes or wings are moved bodily up and down as well as forward and back with respect to the body of the car and the form of such planes or wings will result in the device lifting itself off the ground and propelling itself along.

To describe my invention so that others versed in the art to which it pertains can make and use the same I have illustrated it on the accompanying two sheets of drawings forming a part of this specification, in which:

Figure 1, is a plan view of an air ship, embodying my invention; Fig. 2, is a side elevation of the same and Fig. 3, is a section on line 3—3 of Fig. 1.

Similar reference characters refer to similar parts throughout the several views.

The body of the ship may have any desired form and be of a size to accommodate the engine 4 and one or more passengers. The body is preferably made flat on the bottom and may be provided with suitable wheels 5 for convenience in moving the ship along the ground. Two or more cross shafts 45 6 and 7 are mounted in suitable bearings 8 secured to the body. Each end of each shaft 6 and 7 is provided with a crank arm 9 just outside of the bearings 8 and the extremity of each arm 9 is provided with a 50 crank pin 10 which crank pins are extended out a material distance on either side of the

body and have pivotally secured thereto the planes or wings 11. The planes or wings 11 on each side of the body of the ship are connected by a suitable brace 12 so that the 60 said connected planes or wings are always retained in approximately the same plane which is parallel with the longitudinal axis of the ship body.

Each shaft 6 and 7 has rigidly secured 65 thereon a sprocket wheel 13 which is operatively connected by means of the chain 14 to the small sprocket wheel 15 driven by the motor or engine 4 by means of suitable gearing 16. Each plane or wing 11 is formed 70 with a pocket on its under side which is made of some considerable depth at the front end 17 and gradually slopes toward the rear end 18 where there is no pocket. This pocket on the under side of each plane 75 or wing is designed to lift the ship upward and propel it forward when the shafts 6 and 7 are rotated, and may be varied considerably without departing from the scope of 80 the invention.

Two rudders 19 and 20 are provided on the rearward extension 21 of the body for guiding the ship in its course. The rudder 19 connected by a suitable chain 22 to the operating wheel 23 is for guiding the ship 85 from side to side while the rudder 20 connected by a suitable chain 24 to the operating lever 25 is for guiding the ship up and down. An operator's seat 26 is provided in close proximity to the operating wheel 23 90 and lever 25.

In operation the motor 4 is started and constantly rotates the shafts 6 and 7 clockwise as viewed in Fig. 2, thus, the ship body and contents being heavier than the planes 95 or wings, the planes or wings are made to constantly pass in a circle with the axles of the shafts 6 and 7 as the centers. The pocket formed planes or wings 11 cause the ship to rise and move forward, and the operator by manipulating the wheel 23 and lever 25 guides the ship as desired.

If the engine or motor 4 should stop or refuse to operate properly while the ship is high above ground the planes or wings will 105 act as a parachute and only permit the ship to descend at a slow rate of speed, and thus a perfectly safe air ship is provided.

Having thus fully described my invention what I claim as new and desire to secure by 110 Letters Patent of the United States is:

1. In a device of the class described, a

- suitable body portion, suitable uprights, on each side of the body at the front, suitable uprights on each side of the body near the back, a shaft journaled in the upper ends of said first named uprights, a shaft journaled in the upper ends of said second named uprights, means for rotating said shafts in unison, integral cranks formed on the extremities of both of said shafts, a separate pocket formed plane pivotally mounted on each of said cranks and a rigid brace connecting each fore and aft pair of planes to retain the planes parallel to the body portion.
- 15 2. In a device of the class described, a suitable body portion comprising a boat provided with wheels to support the same when upon the ground, a motor in said body, suitable uprights on each side of the body 20 at the front, suitable uprights on each side of the body at the rear, a shaft journaled in the upper ends of said first named uprights, a shaft journaled in the upper ends of said second named uprights, suitable gearing connecting said shafts with said motor 25 for rotating the shafts in unison, integral cranks formed on the extremities of both of said shafts, a separate pocket formed plane pivotally mounted on each of said cranks and a rigid brace connecting each fore and 30 aft pair of planes to retain the planes parallel to the body portion.
- 15 2. In a device of the class described, a suitable body portion comprising a boat provided with wheels to support the same when upon the ground, a motor in said body, suitable uprights on each side of the body 20 at the front, suitable uprights on each side of the body at the rear, a shaft journaled in the upper ends of said first named uprights, a shaft journaled in the upper ends of said second named uprights, suitable gearing connecting said shafts with said motor 25 for rotating the shafts in unison, integral cranks formed on the extremities of both of said shafts, a separate pocket formed plane pivotally mounted on each of said cranks and a rigid brace connecting each fore and 30 aft pair of planes to retain the planes parallel to the body portion.

In testimony whereof, I have signed my name to this specification in presence of two subscribing witnesses this 30th day of December, 1913, at Chicago, Illinois.

MAX SINGELMANN.
